CLAIM

The ornamental design for a foldable commodity display box, as shown and described.

DESCRIPTION

FIG. 1 is a front view of a foldable commodity display box showing my new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a perspective view thereof;

FIG. 8 is a perspective view thereof in an alternate position, wherein the foldable commodity display box is folded;

FIG. 9 is a perspective view thereof in another alternate position, wherein one large side plate of four side plates of the foldable commodity display box is folded;

FIG. 10 is a perspective view thereof in yet another alternate position, wherein one small side plate of the four side plates of the foldable commodity display box is folded;

FIG. 11 is a cross-sectional view taken along lines 11-11 of FIG. 6; and,

FIG. 12 is a perspective view thereof, showing the foldable commodity display box in an upside-down position stacked upon another foldable commodity display box.

The broken lines in the drawings illustrate environmental subject matter and form no part of the claimed design.
